chinery Corporation, Flemington, N. J., a cor-
poration of New Jersey

Application May 25, 1949, Serial No. 95,226

28 Claims. (Cl. 12—7.5)

1

This invention relates to machines for shaping shoe uppers and is herein illustrated as embodied in a machine for shaping stitchdown uppers over lasts and for pressing together the outwardly flanged upper materials and a shoe sole. As herein illustrated the present invention is embodied in a machine of the type shown, for example, in United States Letters Patent No. 1,861,832, granted June 7, 1932, on an application filed in the name of William C. Baxter and in United States Letters Patent No. 2,226,754, granted December 31, 1940, on an application filed in the name of Albin C. Eek et al. It is to be understood, however, that the invention is not limited in scope to machines for shaping stitchdown uppers over lasts, the invention in certain aspects thereof being equally applicable to machines for shaping uppers other than stitchdown uppers and to machines for shaping uppers over forms other than lasts.

In shaping stitchdown uppers over lasts it has been the practice heretofore to shape the toe portion in a machine constructed for that specific operation and to shape the heel portion in another machine constructed for that operation and finally to shape the side portions of the upper over the last in a device or machine particularly suited to that operation. Thus the complete shaping of a stitchdown upper over a last heretofore required three separate and distinct operations on three different machines, and usually by three different operators. While this system is considered expeditious and satisfactory in the manufacture of shoes in the adult sizes in which the variations in heel heights and toe spring make it difficult to shape the entire upper over a last in a single operation, manufacturers of stitchdown shoes in the juvenile sizes have found this system too expensive and unduly complicated. To improve the facilities for manufacturing stitchdown shoes in the juvenile sizes it is an object of the present invention to provide a machine for shaping uppers over lasts having instrumentalities for shaping the toe, heel and side portions of a stitchdown upper in a single operation.

With the above object in view the present invention in one aspect thereof consists in the provision in a machine for shaping stitchdown uppers over last of work supporting means, herein illustrated as plates constructed and arranged to engage the entire bottom surface of a sole, grippers constructed and arranged to engage outwardly flanged upper materials at opposite sides of the forepart of an upper mounted on a last

5 supported on a sole on said plates, and a plurality of wipers constructed and arranged to engage the entire extent of the outwardly flanged margins of the upper materials. To cause the upper to be tensioned over the last and to cause the sole and the outwardly flanged margins of the upper materials to be pressed together and adhesively attached to each other between said wipers and said sole supporting plates, the machine is provided with an actuator, herein illustrated as a cam shaft, and connections from said actuator for closing the gripper jaws on the work and for moving the sole supporting plates upwardly to bring the entire margin of the sole into intimate contact with the outwardly flanged upper materials. In another aspect thereof the invention relates to the provision, in a machine for shaping stitchdown uppers over lasts having toe wipers, heel wipers, forepart grippers and sole pressing means, of 10 manually operated means for initially closing the forepart gripper jaws on the outwardly flanged margins of the shoe upper materials, means herein illustrated as a detent for holding the gripper jaws closed on the work, power operated means for further closing the gripper jaws and actuating them to tension the upper over the last, and means herein illustrated as a lever actuated by said power operated means for disengaging said detent so that the gripper jaws will open at the appropriate time in the machine cycle. The opening of the gripper jaws is usually timed to occur in the course of the upward movement of the sole supporting plates and just before such upward movement of the plates has brought the upper into a position in which the wipers register substantially with the edge of the last bottom.

40 The present invention in another aspect thereof consists in the provision in a machine for shaping uppers over lasts of a pair of end wipers constructed and arranged for pivotal closing movement about an axis coincident with the adjacent ends of their wiping edges, these being the toe wipers in the illustrated machine, a second pair of end wipers constructed and arranged for closing movement about axes offset laterally from their respective wiping edges, these being the heel wipers in the illustrated machine, a pair of side wipers constructed and arranged to operate on opposite side portions of an upper in the machine, and a pair of thin forepart wipers secured to the toe wipers and arranged to form a junction with the side wipers, 45 thus obviating the occurrence at each side of the

shoe of an area which is not engaged and shaped by the wipers. The illustrated side wipers operate in conjunction with the heel wipers, moving bodily toewards with the heel wipers and having operative movement widthwise of the shoe. At their toe ends the respective side wipers are recessed in order to provide clearance for the operation of the thin forepart wipers above referred to. The wiper assembly is herein illustrated as embodied in a machine for shaping stitchdown uppers over lasts but it is to be understood that the invention in its application to the wiper assembly above defined is not limited in scope to machines for shaping stitchdown uppers over lasts but is equally applicable to machines for operating on the uppers of shoes other than stitchdown shoes. The wiper assembly herein illustrated would, for example, find utility in the shaping of prewelt uppers over lasts.

In accordance with a further feature of the invention the heel and side wiper assemblies are mounted in a carriage which is movable longitudinally of a shoe in the machine. The heel wipers are mounted in a first slide and the side wipers are mounted in a second slide. The first slide is mounted in a guideway in the second slide and the second slide is mounted in a guideway in the carriage for movement to bring the wipers into and out of operative position. It will be understood that it is within the scope of the present invention to arrange a carriage such as the carriage above referred to, to mount a combination of toe wipers and side wipers, if desired. In accordance with a further feature of the invention the first slide, above referred to, is provided with a shoe abutting member constructed and arranged to determine the extent of the wiping movement of the end wipers longitudinally of the shoe. Mounted on the illustrated second slide is a holddown which engages the last on which the upper is mounted and holds it against movement relatively to the upper heightwise thereof. In the illustrated organization the first slide is yieldingly held in an advanced position relatively to the second slide so that the end wipers operate prior to the side wipers. Operating connections are provided between the first slide and the side wipers whereby said side wipers are actuated by relative movement of the first slide and the side wipers longitudinally of the shoe after the end wipers have engaged the shoe. In the illustrated organization rack teeth formed in said first slide and gear segments formed in the side wiper carriers provide the means for actuating the side wipers. In the illustrated machine the first slide is mounted in the second slide which in turn is mounted in the carriage and means herein illustrated as a manually controlled pawl is provided for holding said second slide against retracting movement relatively to the carriage. In the operation of the illustrated machine actuating means advances the carriage longitudinally of the shoe advancing said slides as a unit until the first slide is arrested by the engagement of the shoe abutting member above referred to with an end portion of the shoe. Continued advancement of the carriage causes the second slide to approach the first slide thus causing the rack and segment mechanism above defined to impart wiping movements to the side wipers.

These and other features of the invention will now be described with reference to the accom-

panying drawings and pointed out in the appended claims.

In the drawings,

Fig. 1 is a left side elevation, partly broken away, illustrating one station only of a two-station machine embodying the features of the present invention;

Fig. 2 is an enlarged view in right side elevation, illustrating a portion of the treadle operated mechanism of the machine illustrated in Fig. 1;

Fig. 3 is a front elevation illustrating the upper portion of the station at the left of the machine;

Fig. 4 is a plan view of that station illustrated in Fig. 3, certain parts being broken away to disclose underlying parts;

Fig. 5 is an enlarged sectional view taken substantially on the line V—V of Fig. 4;

Fig. 6 is a plan view similar to Fig. 4 showing the operating parts as they appear at the end of their cycle of operation;

Fig. 7 is a plan view of the carriage and the mechanism mounted therein, certain parts being broken away to disclose underlying parts;

Fig. 8 is a section taken substantially on the line VIII—VIII of Fig. 7;

Fig. 9 is a side elevation of the carriage with a portion of its side wall broken away;

Fig. 10 is a plan view similar to Fig. 4 showing the carriage fully retracted;

Fig. 11 is a section taken substantially on the line XI—XI of Fig. 7; and

Fig. 12 is a sectional elevation of the work supporting plates taken on the longitudinal median line of a shoe supported thereon.

The invention is illustrated in the drawings as embodied in a machine for shaping the uppers of stitchdown shoes over lasts. In the operation of the illustrated machine the outwardly flanged portions of an upper, counter, and lining assembled on a last are cemented together and cement attached to the heel end portion of an extension sole tacked to the last bottom. The shoe parts assembled on a last, arranged in right side up position, are mounted on horizontal work supporting plates, and are arranged relatively to the operating instrumentalities of the machine by advancing the assembly toewards to bring it into engagement with a pair of toe wipers arranged in retracted position. A heel carriage is then advanced horizontally toward the heel end of the shoe from a remote position to bring the heel wipers and side wipers into registration with the work. Thereupon a treadle is depressed to cause portions of the outwardly flanged margin of the upper at opposite sides of the forepart to be engaged by grippers which operate subsequently to tension the upper over the last. After bringing a last holddown member into engagement with the cone portion of the last another treadle is depressed to operate a clutch to initiate the power cycle of the machine. The illustrated machine is substantially similar in its general organization to the machine disclosed in the Baxter patent, and includes certain features disclosed in the Eek et al. patent, said patents being hereinbefore identified.

Referring to Fig. 1, the numeral 20 identifies a standard in which is journaled a motor driven shaft 22 and a cam shaft 24 operatively connected to the shaft 22. Cams fixed to the shaft 24 operate a lever 26 to advance a pair of toe wiper plates, a lever 28 which actuates tip line grippers at the left side of the machine, a similar

lever (not shown) which operates tip line grippers at the right side of the machine, and a thrust member or arm 30 which actuates toggle members 32 and 34 to impart upward movement to a sliding post 36 which mounts work supporting plates hereinafter described. The thrust member 30 also operates a link 38 which carries a spring 40 which operates mechanism for advancing a heel carriage 42 to actuate a pair of heel wiper plates and a pair of side wiper plates. The operation of the cam shaft 24 is controlled by a one revolution clutch mechanism (not shown) which is operated by the depression of a treadle 44.

Referring to Fig. 1 illustrating the forepart grippers at the left side of the machine and their operating mechanism, said grippers comprise a lower jaw 46 fixed to an upward extension 48 of the head 50 of a vertical shaft 52 slidably mounted for vertical movement in fixed bearings 54 and 56, and an upper gripper jaw 58 slidably mounted for vertical movement between the jaw 46 and the extension 48 and normally held elevated by a spring 60. As seen in plan view in Fig. 4, the outer edges of the gripper jaws are in the form of an arc struck from the axis 128 of the shaft 52. The shaft 52 is supported at its lower end by the left end portion of a horseshoe shaped plate 62 fixed to the upper end of a shaft 64 constructed and arranged for vertical movement by the operation of a lever 66 having a fulcrum 68 and a pivotal connection at 70 on the sliding post 36. For initially closing the gripper jaws 46 and 58 on the outwardly flanged margin of an upper mounted on a last arranged in upright position on work supporting plates hereinafter described, a short treadle 72 is pivotally mounted at 74 in the base of the standard. Two links 76 and 78 pivotally mounted on a slide 80 connect the treadle 72 to a lever 82 which, upon depression of the treadle, imparts upward movement to the horseshoe shaped plate 62 to close the gripper jaws. The closing of said jaws consists in imparting upward movement to the lower jaw 46 while the upper jaw 58 is held against upward movement by a fixed plate 84 forming a part of the toe head 86. The lower link 78 is slidably mounted in a bore in a block 88 mounted for swiveling movement on the treadle 72. A spring 90 surrounding the link 78 and positioned between the block 88 and a washer 92 supported by a nut 94 normally holds the treadle 72 in its elevated position shown in Fig. 1. Referring to Fig. 2, the slide 80 is mounted for vertical movement in a guideway 96 formed in a bracket 98 secured to the front of the standard 20. The slide 80 has a vertical portion 100 which provides a pivotal mounting for the links 76 and 78. The slide has also horizontal cylindrical portions 101 and 103 which provide a mounting for a detent 102. The detent is a cylindrical member slidably mounted in a bore in said cylindrical portions and has at its left end, as seen in Fig. 2, a tooth constructed and arranged to engage ratchet teeth 104 formed in the fixed plate 106, and has at its right end a tail 108 projecting through a bore in the end wall of the cylindrical portion 103 and outwardly therefrom beyond the vertical arm 110 of a bell crank lever having a fixed fulcrum 112. A pin 114 projecting from the tail 108 lies in the path of movement of the vertical arm of the bell crank lever. The detent 102 is normally held in ratchet engaging position by a spring 116 surrounding that portion of the tail 108 within the cylindrical portion 103.

An adjustable screw 118 at the free end of the horizontal arm 120 of the bell crank lever lies in the path of upward movement of a spring pressed plunger 121 mounted in an extension of the left side portion of the link 32, said extension being shaped to provide a shoulder 123 from which the plunger projects as shown in Fig. 1. Upward movement of the toggle member causes counterclockwise movement of the bell crank lever as seen in Fig. 2. It will be seen that during such counterclockwise movement the vertical arm 110 of the bell crank lever engages the pin 114 and retracts the detent 102, thus disengaging it from the ratchet teeth 104. The retraction of the detent is timed to occur just before a cam member 122 mounted at the upper end of the shaft 64 moves horizontally into engagement with a roll (not shown) to effect a downward movement to the horseshoe shaped plate 62 sufficient to permit the spring 60 to open the gripper jaws 46 and 58, permitting them to be moved out of engagement with the upper. It will be seen that during the downward movement of the horseshoe shaped plate 62 the lever 82 swings in a counterclockwise direction causing upward movement of the slide 80, and the detent 102 must be retracted at this time so that it will not obstruct such movement of the slide. In the operation of the machine the gripper jaws 46 and 58 move outwardly and towardly in an arcuate path to tension the upper over the last while the grippers remain closed on the work, and after the gripper jaws are opened as above described further arcuate movement of the jaws carries them into a position remote from the work. The arcuate movement of the jaws is effected by the operation of the cam lever 28 acting through connections including a link 124 and a turn buckle 126 which serves as a means for adjusting the gripper jaws widthwise of a shoe in the machine. It will be understood that the above description of the construction and operation of the gripper mechanism at the left side of the machine applies equally well to the corresponding mechanism at the right side of the machine and that the two-gripper mechanism operates simultaneously to tension the upper over the forepart and instep portion of the last. A more detailed description of those features of the construction and operation of the gripper mechanism not specifically set forth herein will be found in the patent to Eek et al. No. 2,226,754 hereinbefore referred to.

Referring to Fig. 4, the illustrated machine is provided with a pair of toe wipers 130, a pair of heel wipers 132 and a pair of side wipers 134 which operate on opposite side portions of the shoe between the breast line region and the region of the tip line. The side wipers 134 are constructed to operate on three consecutive half sizes, there being five sets of side wipers for the left foot shoe and five sets for the right foot shoe in the run of juvenile sizes from 2 to 9. In the same run two sets of toe wipers are required for the left foot shoe and two sets for the right foot shoe, one set operating on sizes from 2 to 6 and the other set on sizes from 6½ to 9. The heel wipers are universal for the entire run from size 2 to size 9 and operate on both right and left foot shoes. A pair of short, thin flexible wiper plates 136 are secured by screws 137 (Fig. 5) in recesses in the bottom surfaces of the toe wipers respectively, said recesses being constructed and arranged to position the wiper plates 136 accurately relatively to the toe wipers so that the wip-

ing edge of each wiper plate 136 is accurately aligned with the wiping edge of the toe wiper to which it is attached as shown in Fig. 4. The wiper plates 136 serve to bridge the gap which occurs between the toe wipers and the side wipers when operating on the larger sizes in the range on which the wipers are intended to operate. The wiper plates 136 are of universal construction and consequently only one set is required for each station of the machine. The position of the side wipers relatively to the heel wipers remains substantially constant and consequently no provision is made for bridging the slight gap that occurs between them. The toe wipers 130 are secured by screws 138 to wiper carrier plates 140. The path of movement of each of the wiper carrier plates is determined by two fixed rolls 142 and 144 positioned in arcuate slots 146 and 148 formed in the wiper carrier plate. These slots are so constructed and arranged that the toe wiper plates advance bodily, heelwardly while simultaneously closing on the toe portion of the shoe in the machine. The wipers are advanced by the operation of the cam lever 26 (Fig. 1) which has mounted in its upper end portion a screw 149 constructed and arranged to engage the end of a stem 151 projecting from a cross bar 153 (Fig. 4) which is connected by a link 155 to a pivot pin 157 projecting downwardly from the wiper carrier plate 140. The screw 149 is adjustable in the cam lever 26 to vary the space which exists between the screw and the stem when the machine is at rest thereby adjusting the extent of the operative movement of the toe wipers. The mechanism through which the cam lever 26 actuates the toe wipers is specifically illustrated and described in the Baxter patent hereinbefore identified.

Each of the heel wipers 132 has an upwardly extending cylindrical boss 154 (Fig. 8) which is mounted for rotary movement in a bore in a heel wiper carrier or slide 156 and retained therein by a headed screw 152 mounted in a tapped hole extending through the center of the boss and into the wiper plate. The illustrated heel wipers are of the butting point type, so called, characterized by the meeting of the ends of the wiping edges at the back line portion of a shoe in the machine (Fig. 7). The butting end portions 153 of the wiper plates extending from the meeting point of the wiping edges are each in the form of an arc struck from the center of screw 152, thus providing for angular movement of the heel wiper plates about said screws. In Fig. 7 the heel wipers are shown in the position relatively to each other which they occupy when they are closed on the work. The wipers are normally held in their open position with their outer edges 158 abutting shoulders 160 formed in the wiper carrier. To this end, a flat spring 162 having forwardly bent arcuate sections is secured to a central portion of the shoulder 160 by a headed screw 164, the arcuate sections of said spring being arranged to engage respectively the rear edge faces of the heel wiper plates. Referring to Fig. 11, the heel wiper carrier 156 is provided at its rear end portion with an upward extension 166 terminating widthwise in outwardly projecting tongues 168 which are mounted for sliding movement lengthwise of a shoe in the machine in grooves formed in a carrier plate or slide 170 which, in turn, is mounted for sliding movement lengthwise of the shoe in rabbeted portions 172 of a carriage 174. Mounted in the heel wiper carrier 156 is a pin 176 which projects

upwardly from the carrier into a slot 178 (Fig. 7) which determines the limits of movement of the heel wiper carrier relatively to the carrier 170. Referring to Fig. 8, the heel wiper carrier is normally held at the limit of its toward movement relatively to the carrier 170 by a spring 180 mounted on a rod 182 projecting from a downward extension 184 of the carrier 170 in the direction of the heel end of a shoe in the machine, said rod being arranged in alignment with a bore 186 in the wiper carrier in which said spring is seated. Referring to Fig. 11, the carrier 170 is provided at each side thereof with a downwardly extending headed stud 188 on which there is pivotally mounted a carrier 190 for one of the side wipers 134. Referring to Fig. 7, the carrier 190 is swung in a counterclockwise direction about the stud 188 to advance the side wiper 134 at the right side of the shoe by the operation of rack teeth 192 formed in an outward extension 194 of the heel wiper carrier 156 with a gear segment 196 formed in the carrier 190. The above description of the rack and segment mechanism for operating the side wiper 134 at the right side of the shoe applies equally well to the rack 198 and gear segment 200 at the left side of the shoe. The segments are so arranged relatively to the rack teeth that the side wipers 134 are in their retracted position shown in Fig. 7 when the heel wiper carrier 156 is at the limit of its movement toward the heel end of the shoe in which position it is normally held by the spring 180. Thus it will be seen that the heel wipers 132 and the side wipers 134 are both normally held in their respective retracted positions when there is no shoe in the machine.

In order that the crease lines formed in the upper by each of the side wipers 132 will be in substantial alignment with the crease lines formed by the toe wipers 130 the side wiper carriers must be accurately located heightwise of the shoe with the wiping edges of the side wipers accurately aligned with the wiping edges of the toe wipers. To this end means is provided in the illustrated machine for holding the forward end portion of each of the side wiper carriers in accurately predetermined position heightwise of the shoe and for preventing vertical movement of the side wipers in response to the upward movement of the shoe during the upper shaping operation. Referring to Figs. 6 and 9, the slide 170 has an extension 171 at each side thereof and each of these extensions is strengthened by an upwardly extending flange 173 running from the extremity of the slide at its outer edge inwardly and toewardly toward the shank portion of the shoe in the machine, then curving heelwardly and running to a point in line with a boss 241 projecting upwardly from the slide, then turning and running inwardly to form a junction with said boss. The curved portions of the extensions 171 lying at opposite sides of the shank portion of the shoe in the machine overlie the side wiper carriers. Referring to Fig. 9 it will be seen that the plane bottom surface of the extension 171 is arranged in contiguous relation to the plane top surface of the side wiper carrier 190 and holds said carrier against upward movement without restricting operative movement thereof. Each side wiper carrier is supported from beneath by an arm 175 projecting downwardly from the bottom surface of the slide 170 and extending horizontally to a point substantially in vertical alignment with the extremity of the extension 171. At its extremity each arm 175 is

provided with a land 171 having a plane top surface which engages the plane bottom surface of the wiper carrier and maintains a contiguous relation between the carrier and the extension 171 as shown in Fig. 9. The extension 171 and the arm 175 are accurately spaced relatively to each other in a vertical direction to permit free sliding movement of the wiper carrier between them while preventing any appreciable vertical movement thereof.

The slide 170 which carries the heel wipers and the side wipers is manually advanced from its position illustrated in Fig. 10 to bring the wipers into engagement with an upper such, for example, as the upper 202 illustrated in Fig. 10 mounted on a last 204. The shoe at this time is supported slightly below its lasting position so that the heel wipers and side wipers engage the upper 202 on a line slightly above the plane of the last bottom. In order to facilitate the manual advancement of the slide 170 said slide is provided with two upstanding handles 206 (Fig. 3). For holding the slide against return movement after its manual advancement a detent 208 (Fig. 8) is mounted in a bore in the downward extension 184 of the slide and arranged to engage ratchet teeth formed in a plate 210 secured to the upper surface of the base of the carriage 42. The detent has an upwardly extending stem 212 surrounded by a spring 214 which urges the detent downwardly into ratchet engaging position. The detent is moved upwardly to permit the return of the slide to its position shown in Fig. 10 by the manual operation of a bell crank lever 216 pivotally mounted at its elbow on a pin 218 mounted in ears formed in the slide 170, one of said ears being identified by the numeral 220 in Fig. 8. As shown in Fig. 3 the handle 221 at the upper end of the vertical arm of the bell crank lever 216 is so located with relation to the handles 206 that the operator may conveniently operate it with either thumb while gripping the handles 206 with both hands. The horizontal arm of the bell crank lever is bifurcated to receive the upper end portion of the stem 212 which has its opposite sides slabbed off so that it fits into the bifurcated portion of the lever. A cross pin 222 in the stem 212 provides a connection between the stem and the bell crank lever, said lever being notched to receive said cross pin. The slabbed off upper end portion of the stem 212 is accurately fitted into the bifurcated portion of the bell crank lever in order that a correct orientation of the detent relatively to the ratchet teeth will be maintained.

In the operation of the machine the shoe is moved upwardly to cause the wipers to wipe the upper downwardly to the bottom of the last, and thereupon the wipers are advanced slightly to form a well defined crease line at the apex of the angle defined by the body portion of the upper and its outwardly flanged margin. At the heel end of the shoe the extent of the advancement of the heel wipers 132 to form a crease line in the upper is determined by the engagement of a leather-faced abutment member 224 (Fig. 8) with the heel end portion of the upper thereby arresting the advancement of the heel wiper carrier 156. In the course of the manual operation of the slide 170 the heel wiper carrier 156 and the slide 170 advance as a unit until the abutment member 224 engages the heel end portion of the shoe and thereupon the slide 170 advances relatively to the heel

wiper carrier 156 thereby actuating the gear segment 196 and 200 (Fig. 7) to swing the side wipers 134 into upper engaging position. In the power operation of the machine the slide 170 is further advanced to complete the operation of the heel wipers and the side wipers. The heel abutment member is in the form of an upstanding head the upper facing surface of which is shaped generally complementally to the contour of the heel end portion of the shoe and has a horizontal shank portion 226 which fits into a groove 228 formed in the heel wiper carrier 156 and is slotted to receive a headed clamping screw 230 (Fig. 8). Thus it will be seen that the abutment member is adjustable lengthwise of a shoe in the machine to vary the extent of the movement of translation of the heel wipers toewards in their upper creasing operation.

The advancement of the heel wipers inwardly under the last bottom has a tendency to cam the heel portion of the last upwardly thus misplacing the last relatively to the upper. In order to control this tendency a last holdown is mounted on the slide 170 and arranged to be brought into position over the cone portion of the last. The illustrated holdown member is in the form of a plunger 232 (Fig. 9) having at its lower end a flat head constructed for engagement with the plane surface at the upper extremity of the cone portion of the last. The plunger is mounted in a barrel 234 which is adjustably secured by a split clamp 236 at the free end of an arm 238 mounted for free swinging movement on a post 240 projecting upwardly from a boss 241 on the slide 170. The plunger 232 is provided at its upper end with a stem 242 which is surrounded by a spring 244 which expands between the head of the plunger and a shoulder at the upper end of the barrel to urge the plunger downwardly. The normal position of the plunger, as shown in Fig. 9, is determined by the engagement of a stop nut 246 with the upper end of the barrel 234. In order to hold the arm 238 yieldingly in the position in which it is located by the operator a spring washer 252 backed up by a nut 254 presses against the hub 248 of said arm.

In order to prevent accidental removal of the slide 170 from the carriage 42 a plunger 256 is mounted in a bore in oppositely extending bosses 260 and 266 in the base of the carriage and is normally held by a spring 258 in the position shown in Fig. 9 wherein the head of the plunger projects upwardly from the boss 260 into the path of movement of the left arm 175 secured to the bottom of the slide 170. To facilitate the retraction of the plunger 256 to permit the removal of the slide 170 from the carriage 42 a knurled head 264 is secured to the stem of the plunger and arranged to engage the downwardly extending boss 266.

To provide for the power operation of the heel wipers and side wipers, the carriage 42 has downwardly extending legs 268 (Fig. 9) which are bored horizontally for sliding engagement with two cylindrical horizontal rails 270 each of which is mounted in and secured to uprights 272 formed in a plate 274 fixed to the upper portion of the standard 20 and the carriage is actuated by a movement of the thrust member 30 to the right as seen in Fig. 1, the right end portion of said thrust member being pivotally connected to the head 276 of the rod 38 the opposite end of which is slidably mounted in a bearing in a yoke 278 which is connected to a lever 280 by a cross

pin 282 secured in the yoke 278 and extending through a slot 284 provided in the lever 280. In the operation of the machine the cross pin 282 moves freely in the slot 284 until it engages the end of an abutment screw 286 mounted in the lever 280 and arranged to extend into the upper portion of said slot. The screw 286 may be adjusted to determine the extent of the lost motion of the yoke 278 relatively to the lever 280. By so adjusting the screw 286 the extent of the operative movement of the carriage 42 is determined. Referring to Fig. 8, the upper portion of the lever 280 is bifurcated to receive in sliding engagement a block 288 pivotally mounted on a cross pin 290 fixed to ears 292 projecting downwardly from the base of the carriage. The normal retracted position of the carriage 42 is determined by the engagement of a spring pressed plunger 294 (Fig. 1) carried by an extension of the lever 280 with the bottom surface of the plate 274. In order to provide a yielding action of the heel wipers and side wipers on the shoe the thrust member 30 operates through the spring 40 surrounding rod 38 and positioned between the head 276 and the yoke 278. A collar 296 (Fig. 3) secured to that portion of the rod 38 projecting into the yoke 278 determines the normal rest position of the carriage.

While it has been found that the toe wipers, the heel wipers, and the outside shank wiper operate satisfactorily on the entire run of sizes for which they are intended, it is desirable to provide for adjustment of the inside shank wiper lengthwise of the shoe to insure a satisfactory lasting operation on the inside of the shank where the last bottom line has a pronounced inward curvature in some types of lasts. To that end each of the side wiper carriers is provided with a slot 298 (Fig. 7) for mounting a wiper attaching screw 300 the opposite sides of which are slabbed off to hold the screw against turning movement in said slot. As herein illustrated the head of the screw 300 engages the bottom of the wiper (Fig. 8) and a clamping nut 302 is threaded onto the upwardly projecting portion of the screw. Referring to Fig. 7, a washer 304 having an extension in the form of a pointer is mounted on the screw 300 and held against rotation relatively to the screw by providing a screw receiving opening in the washer having parallel edges which engage the slabbed off side portions of the screw. The pointer provided by the washer registers with a scale formed on the wiper carrier and indicating by suitable characters the range of sizes on which the wiper operates. To facilitate the changing of the side wipers 134 each of said wipers is provided with a notch 305 (Fig. 7) extending inwardly from its outer edge and terminating in a cylindrical surface of the same curvature as the screw 300. Thus it will be seen that the side wipers may be readily removed from their carriers after releasing the clamping nuts 302 sufficiently to relieve the clamping pressure and another set of wipers may be readily mounted on the carriers and secured thereto. The side wipers are correctly oriented for operative movement by bringing the beveled edge faces 307 formed in said wipers into engagement with complementally beveled shoulders formed in the wiper carriers.

For supporting in upright position a stitchdown upper assembled, together with an extension sole, on a last, the illustrated machine is provided with a work supporting plate 306 (Fig.

10 12) constructed and arranged to support shoes in the run of juvenile sizes from 2 to 9 inclusive. The plate 306 is secured to a carrier 308 fixed to the upper end portion of the post 36 (Fig. 1). As shown in Fig. 12, the plate 306 is recessed from its longitudinal central portion heelwardly and in this recessed portion there is mounted any one of a plurality of heel supporting plates. For shoes having spring heels six such plates are provided in the run of sizes from 2 to 9, there being one set of three plates for right foot shoes and another set for left foot shoes. One plate is provided for sizes 2 to 3½, a second for sizes 4 to 6, and a third for sizes 6½ to 9. For shoes which are not provided with spring heels, these being for the most part shoes in the smaller infant sizes, a heel supporting plate having a plane work supporting surface is constructed and arranged to be mounted in the recess in the plate 306. For positioning any one of the heel supporting plates above referred to on the plate 306 a shoulder 312 is provided at the forward extremity of the recess in the heel portion of the plate 306 and two dowel pins 314 are arranged to project upwardly from the plate 306 and to register with bores in the heel supporting plate. The surface contour of the top of the plate 316 illustrated in the drawings is complementary to the contour of the sole of a shoe of the type generally indicated by broken lines in Fig. 12, said shoe being characterized by a spring heel inserted between the heel portion of the outsole and the shoe bottom. The heel supporting plate 316 has at its forward end a horizontal plane surface 318 which is elevated relatively to the horizontal surface 316 of the body portion of the plate, said surfaces being separated by a beveled surface 320 which, as shown in Fig. 10, extends diagonally across the upper surface of the plate and registers with the heel breast portion of the outsole. Referring to Fig. 3, the carrier 308 is provided with uprights 322 which are flanged outwardly at their upper ends to support the heel end portion of the plate 306, the plate being secured to said uprights by two screws 324 (Fig. 12). At its toe portion the plate 306 is positioned relatively to the body portion of the carrier 308 by the dowel pins 326 projecting upwardly from the carrier into sockets in the plate. The toe supporting surface 328 of the plate 306 is downwardly inclined heelwardly to a slight extent to compensate, at least in some degree, for the toe spring of the shoe in the machine. When the machine is at rest the carrier 308 is supported by a boss 330 (Fig. 1) projecting upwardly from the top of the standard 20. When the carrier is in its rest position the work supporting plate 306 is so located vertically with relation to the toe wipers 130 that the outwardly flanged margin of a stitchdown upper together with the extension of the sole may conveniently be inserted between the wipers and the plate, as shown in Fig. 10.

The illustrated machine is constructed and arranged to operate on a stitchdown shoe in which the heel portion as well as the forepart is flanged outwardly for attachment to the margin of an extension sole. Preferably the counter is molded with an outturned flange and the margins of the upper, counter, and lining are adhesively attached to each other and to an extension sole in the operation of assembling the shoe parts on a last. In the preparation of the shoe parts for the operation of the present machine thereon the margins of the upper materials and

the extension of the sole are treated with cement so that the outwardly flanged margins of the upper materials are adhesively attached to the extension sole by the upward pressure of the work supporting plate 306 after the wipers are closed upon the shoe. When the machine is at rest the slide 170 which mounts the heel and side lasting wiper assembly is fully retracted into its position illustrated in Fig. 10 so that the shoe parts assembled on their last may conveniently be mounted on the plate 306 and advanced manually into their position in Fig. 10 in which the toe portion of the upper is in intimate contact with the wiping edges of the toe wipers. After so locating the shoe in the machine the operator manually directs the outturned margins of the upper materials into the gripper jaws 58 and 46 (Fig. 1) at the left side of the machine and into the corresponding gripper jaws of the right side of the machine and depresses the treadle 72 to close the jaws on the work. The arm 238 (Fig. 9) is now swung upon the post 240 to bring the last holdown member or plunger 232 into a position over the cone portion of the last. The plunger will have been adjusted vertically so that it is substantially contiguous to the cone of the last when it is swung into operative position. After the gripper jaws have been initially closed on the work the operator grasps the handles 206 of the slide 170 and advances the slide from its position shown in Fig. 10 into its position shown in Fig. 4. Such advancement of the slide is arrested by the engagement of the heel abutment member 224 with the heel end portion of the upper. It will be understood that the detent 208 (Fig. 8) acting on the ratchet plate 210 serves to hold the slide 170 against return movement during the subsequent power operation of the machine. The operator now depresses the treadle 44 to initiate the power cycle. Thereupon the grippers are operated to tension the upper over the last and the wipers are advanced simultaneously with the upward movement of the work supporting plate 306 thus causing the upper to be wiped heightwise of the last toward the last bottom. The final advancement of the wipers occurs after the plate 306 has come to the limit of its upward movement, such final advancement serving to form a well defined crease line in the upper at the apex of the angle defined by the body portion of the upper and its outturned flange. Upon the completion of the advancement of the wipers and the upward movement of the plate 306 the machine comes to rest with the work held under pressure between the plate and the wipers and the pressure on the work is maintained while another shoe is positioned in the other station of the machine. During the operation of the second station the work supporting plate 306 in the first station moves downwardly to relieve the pressure on the work and the wipers are retracted into their respective positions shown in Fig. 4. While the work is held under pressure in the second station the operator grasps the handles 206 of the slide 170 and operates the handle 221 of the bell crank lever 216 to retract the detent 208 and then retracts the slide 170 into its position shown in Fig. 10, leaving the shoe free to be removed from the machine. The shoe is now completely lasted and the extension sole is cement attached to the outwardly flanged margins of the upper materials about the entire periphery of the shoe.

Having thus described our invention, what we

claim as new and desire to secure by Letters Patent of the United States is:

1. In a machine for shaping stitchdown uppers over lasts, a pair of toe wipers, a pair of heel wipers, grippers at opposite sides of the forepart of the shoe constructed and arranged to tension the upper over a last, means for pressing a sole against the outwardly flanged margins of the shoe upper parts, manually operated means for closing the grippers on the outwardly flanged margins, means for holding the grippers so closed, power operated means for further closing the grippers and actuating them to tension the upper over the last, and means actuated by said power operated means for releasing said holding means.
2. In a machine for shaping stitchdown uppers over lasts, a pair of toe wipers, a pair of heel wipers, grippers at each side of the forepart of the shoe constructed and arranged to engage the outwardly flanged upper materials, a member for holding the grippers closed on the upper, a manually operated actuator for closing the grippers, power operated means for further closing the grippers and actuating them to tension the upper over a last, and a member operated by said power operated means for releasing said holding member so that the grippers will open when the power operated means is released.
3. In a machine for shaping stitchdown uppers over lasts, a pair of toe wipers, a pair of heel wipers, grippers constructed and arranged to engage the outwardly flanged margins of the upper materials at opposite sides of the forepart of the upper, means for pressing a sole against the outwardly flanged margins of the upper materials, an actuator, and connections from said actuator for actuating said wipers and grippers and said sole pressing means in predetermined time relation to each other.
4. In a machine for shaping stitchdown uppers over lasts, a pair of toe wipers, a pair of heel wipers, grippers constructed and arranged to engage the outwardly flanged margins of the upper materials at opposite sides of the forepart of the upper, means for pressing a sole against the outwardly flanged margins of the upper materials, an actuator, connections from said actuator for actuating said wipers and grippers and said sole pressing means in predetermined time relation to each other, said connections including means for adjusting the timing of the advancement of the toe wipers, and means for adjusting the timing of the advancement of the heel wipers.
5. In a machine for shaping stitchdown uppers over lasts, a pair of toe wipers, a pair of heel wipers, a pair of side wipers, grippers at opposite sides of the forepart of a shoe in the machine constructed and arranged to engage the outwardly flanged margins of the upper materials, a presser for bringing a sole into intimate contact with the outwardly flanged upper materials throughout the entire periphery of the upper, an actuator, and connections from said actuator for actuating the elements above defined in predetermined time relation to each other.
6. In a machine for shaping stitchdown uppers over lasts, work supporting means constructed and arranged to engage the entire bottom surface of a sole, grippers constructed and arranged to engage outwardly flanged upper materials at opposite sides of the forepart of an upper, wipers constructed and arranged to engage the entire extent of the outwardly flanged margins of the upper materials, an actuator, and connections

from said actuator for operating the grippers and for actuating the sole supporting means to cause the sole and the outwardly flanged margins of the upper materials to be pressed between said wipers and said sole supporting means.

7. In a machine for shaping uppers over lasts, a wiper assembly constructed and arranged to operate upon the entire lasting margin of a closed upper, said wiper assembly comprising a pair of toe wipers constructed and arranged for pivotal closing movement about an axis coincidental with the adjacent ends of their wiping edges, a pair of heel wipers constructed and arranged for closing movement about axes offset laterally from their wiping edges, a pair of wipers constructed and arranged to operate on opposite side portions of an upper, and a pair of thin forepart wipers secured to the toe wipers and arranged to form a junction with the side wipers.

8. In an upper shaping machine a pair of toe wipers, means for advancing said wipers bodily heelwardly of a shoe in the machine and closing said wipers, a pair of butting point heel wipers each mounted on an axis offset laterally from the butting points of said wipers, a carrier for 25 said heel wipers, means for moving said carrier toewardly thereby to cause said heel wipers to last the heel portion of the shoe, a pair of side wipers constructed and arranged for bodily movement toewardly with the heel wipers and for operating 30 movement widthwise of the shoe, and a pair of thin forepart wipers secured to said toe wipers and extending heelwardly therefrom.

9. In an upper shaping machine a pair of toe wipers, means for advancing said wipers bodily heelwardly of a shoe in the machine and closing said wipers, a pair of butting point heel wipers each mounted on an axis offset laterally from its butting point, a carrier for said heel wipers, means for moving said carrier toewardly thereby to cause said heel wipers to last the heel portion of the shoe, a pair of side wipers constructed and arranged for bodily movement toewardly with the heel wipers and for operating movement 40 widthwise of the shoe, and a pair of thin forepart wipers secured to said toe wipers and extending heelwardly therefrom, said side wipers being recessed to provide clearance for the operation of said forepart wipers.

10. In a machine for shaping uppers over lasts, a pair of end wipers, a first slide on which said end wipers are mounted for closing movement, a pair of side wipers, a second slide on which said side wipers are mounted for movement widthwise of a shoe in the machine, said second slide having a guideway in which the first slide is mounted, a carriage for said slides, said carriage having a guideway in which the second slide is mounted, and means for moving said carriage longitudinally of a shoe in the machine.

11. In a machine for shaping uppers over lasts, a pair of end wipers, a first slide on which said end wipers are mounted for wiping movement, a member mounted on said first slide and arranged to arrest the advancement of said slide by engagement with a shoe in the machine, a pair of side wipers, a second slide on which said side wipers are mounted for wiping movement, a carriage for said slides, and means for advancing said carriage longitudinally of a shoe in the machine.

12. In a machine for shaping uppers over lasts, a pair of end wipers constructed and arranged to operate on a shoe arranged in upright position in the machine, a first slide on which said end

wipers are mounted for closing movement, a pair of side wipers, a second slide on which said side wipers are mounted for movement widthwise of the shoe, a shoe holdown mounted on said second slide, a carriage for said slides, and means for moving said carriage longitudinally of the shoe.

13. In a machine for shaping uppers over lasts, a pair of end wipers, a first slide on which said wipers are mounted for wiping movement, a second slide on which said first slide is mounted for movement longitudinally of a shoe in the machine, a pair of side wipers mounted on said second slide for wiping movement, yielding means for advancing said first slide relatively to said second slide, and means for advancing said second slide.

14. In a machine for shaping uppers over lasts, a pair of end wipers, a first slide on which said end wipers are mounted for wiping movement, a pair of side wipers, a second slide on which said side wipers are mounted for wiping movement, said second slide having a guideway in which the first slide is mounted, and operating connections between the first slide and the side wipers whereby said side wipers are advanced by relative movement of the side wipers and the first slide.

15. In a machine for shaping uppers over lasts, a pair of end wipers, a first slide on which said end wipers are mounted for wiping movement, a pair of side wipers, a second slide on which said side wipers are mounted for wiping movement, and intermeshing gear teeth formed in the first slide and the side wipers respectively whereby the side wipers are advanced by relative movement of the first slide and the side wipers.

16. In a machine for shaping uppers over lasts, a pair of end wipers, a first slide on which said end wipers are mounted for wiping movement, a second slide in which said first slide is mounted for rectilinear movement longitudinally of a shoe in the machine, a pair of side wipers pivotally mounted on said second slide, rack teeth formed in said first slide and gear segments formed in said side wipers and constructed and arranged to mesh with said rack teeth.

17. In a machine for shaping uppers over lasts, a pair of end wipers, a first slide on which said end wipers are mounted for wiping movement, a shoe engaging member mounted on said first slide for adjustable movement longitudinally of a shoe in the machine, a second slide in which said first slide is mounted for rectilinear movement longitudinally of a shoe in the machine, a pair of side wipers pivotally mounted on said second slide, rack teeth formed in said first slide and gear segments formed in said side wipers and constructed and arranged to mesh with said rack teeth.

18. In a machine for shaping uppers over lasts, a pair of end wipers, a first slide on which said end wipers are mounted for wiping movement, a second slide on which said first slide is mounted, a pair of side wipers mounted on said second slide, a carriage on which said second slide is mounted, and means for holding said second slide against retracting movement relatively to said carriage.

19. In a machine for shaping uppers over lasts, a pair of end wipers, a first slide on which said end wipers are mounted for wiping movement, a second slide on which said first slide is mounted, a pair of side wipers mounted on said second slide, a carriage on which said second slide is mounted, ratchet teeth on said carriage, a pawl carried by 75 said second slide, and a manually operated lever

mounted on said second slide and constructed and arranged to retract said pawl.

20. In a machine for shaping uppers over lasts, a pair of end wipers, a first slide on which said end wipers are mounted for wiping movement, a pair of side wipers, a second slide on which said side wipers are mounted for wiping movement, an actuator for advancing said second slide, and yielding means for transmitting the advancement of the second slide to the first slide.

21. In a machine for shaping uppers over lasts, a pair of end wipers, a first slide on which said end wipers are mounted, a pair of side wipers, a second slide on which said side wipers are mounted, a carriage in which both said slides are mounted, means for holding said second slide against movement in one direction relatively to said carriage, an actuator for advancing said carriage, and yielding means whereby the advancement of the second slide is transmitted to the first slide.

22. In a machine for shaping uppers over lasts, a pair of end wipers, a pair of side wipers, a shoe engaging member, means for advancing the end wipers, the side wipers and the shoe engaging member as a unit until said shoe engaging member engages a shoe in the machine, and means rendered effective for actuating the side wipers when the shoe engaging member is thus arrested.

23. In a machine for shaping uppers over lasts, a pair of end wipers, a first slide on which said end wipers are mounted, a shoe engaging member mounted on said slide, a pair of side wipers, a second slide on which said side wipers are mounted, means for advancing said slides as a unit until the first slide is arrested by the engagement of said shoe engaging member with a shoe in the machine and for thereafter advancing the second slide relatively to the first slide, and means actuated by such relative movement of the slides for imparting wiping movement to the side wipers.

24. In a machine for shaping uppers over lasts, a pair of end wipers, a first slide on which said end wipers are mounted, a shoe engaging member secured to said first slide, a pair of side wipers, a second slide on which said side wipers are mounted, a carriage for mounting said slides, means for positively holding said second slide against movement in one direction relatively to said carriage, means for yieldingly holding said first slide against movement in one direction relatively to said carriage, an actuator for advancing said carriage, and means actuated by relative movement of said slides for imparting wiping movement to said side wipers.

25. In a machine for shaping uppers over lasts, a pair of end wipers, a first slide on which said end wipers are mounted, a member secured to said first slide, said member being constructed and arranged to arrest the advancement of said slide by engagement with an end portion of a shoe in the machine, a pair of side wipers, a second slide mounting said first slide and said side wipers, a carriage in which said second slide is mounted, a detent for positively holding said sec-

ond slide against movement in one direction relatively to said carriage, yielding means for holding said slides against relative movement and an actuator for advancing said carriage.

26. In a machine for shaping uppers over lasts, a pair of end wipers, a first slide on which said end wipers are mounted, a shoe engaging member secured to said slide, a pair of side wipers, a second slide on which said first slide and said side wipers are mounted, a spring disposed between said slides and constructed and arranged to hold said slides yieldingly against relative movement in one direction, a carriage for said second slide, and means acting on said carriage first to advance said slides as a unit until the first slide is arrested by the engagement of said shoe engaging member with a shoe in the machine and thereafter to cause the second slide to move relatively to the first slide, and means actuated by such relative movement of the slides for imparting wiping movement to the side wipers.

27. In a machine for shaping uppers over lasts, upper tensioning means comprising a pair of gripper jaws, a manually operated member for initially closing said gripper jaws, means for holding the gripper jaws initially closed, a power operated actuator, connections from said actuator for further closing said gripper jaws and for releasing said holding means, and connections from said actuator for imparting a movement of translation to said gripper jaws.

28. In a machine for shaping uppers over lasts, upper tensioning means comprising a pair of gripper jaws, a manually operated actuator, connections from said actuator for initially closing said gripper jaws, means incorporated in said connections for holding the gripper jaws initially closed, a power operated actuator, connections from said power operated actuator for further closing said gripper jaws and for releasing said holding means, and connections from said power operated actuator for imparting a movement of translation to said gripper jaws.
